UNITED STATES PATENT OFFICE

132,251

DESIGN FOR A PIN OR SIMILAR ARTICLE

Marie Eron, Chicago, Ill.

Application December 20, 1941, Serial No. 104,764

Term of patent 7 years

To all whom it may concern:

Be it known that I, Marie Eron, a citizen of the United States, residing in Chicago, in the county of Cook and State of Illinois, have invented a new, original, and ornamental Design for a Pin or Similar Article, of which the following is a specification, reference being had to the accompanying drawing, forming a part thereof.

Fig. 1 is a plan view of a pin or similar article showing my new design, and

Fig. 2 is an edge view thereof.

I claim:

The ornamental design for a pin or similar article, as shown.

MARIE ERON.
